UNITED STATES PATENT OFFICE.

ARTHUR J. MOXHAM, OF JOHNSTOWN, PENNSYLVANIA.

METHOD OR PROCESS OF MAKING WIRE CABLES.

SPECIFICATION forming part of Letters Patent No. 337,513, dated March 9, 1886.

Application filed September 17, 1884. Serial No. 143,336. (No specimens.)

To all whom it may concern:

Be it known that I, ARTHUR J. MOXHAM, of Johnstown, in the county of Cambria and State of Pennsylvania, have invented a new and useful Method or Process of Making Wire Cables, which invention is fully set forth and illustrated in the following specification and accompanying drawings.

The object of this invention is to make a wire cable which shall have, with a certain degree of elasticity, a greatly increased durability, particularly when used as a traction-cable for cable railways.

The invention consists in the method of manufacture, as hereinafter described, and particularly set forth in the claims.

In the accompanying drawings, Figure 1 shows in cross-section a cable manufactured by my said method. Fig. 2 shows in cross-section a cable made by the same process having two series of strands. Fig. 6 shows in cross-section a cable having two series of strands, one of the series being of solid wire and the other of finer laid up wires. Fig. 4 shows in side view a piece of finished cable made like Fig. 1. Fig. 5 illustrates a piece of one strand of each cable coiled or twisted before being laid up with the other strands forming the cable. Fig. 3 shows in cross-section a cable with a flexible core.

The cables illustrated in said figures (except Fig. 6) are made up of solid strands, preferably treated cold in the process of making the cables.

It is preferable to treat such wires in their cold state for the following reasons:

First. In order to prevent the destruction of the center or core when one is employed, if such core, as is usually the case, be made of material incapable of resisting destruction by contact with heated metal.

Second. If twisted or laid up hot, the set given to the metal wire becomes a dead-set. Such set is for many purposes a great disadvantage, and especially in cables for traction purposes, which cables should retain a certain degree of elasticity.

Third. It is very difficult to heat masses of metal of such small sectional area as compose the wires of a cable to a uniform temperature. Every slight change in temperature, even be-

low that which in itself would destroy or burn the metal, will effect a difference in the tension of its particles. Such deterioration is entirely avoided by transforming the wire into helices 55 while cold. There is therefore lack of homogeneity of metal in the strands composing a hot twisted cable. There is also always present the risk or danger of overheating, and although a single wire is small of itself in mass, 60 yet it forms relatively a large part or section of a cable. Thousands of lineal feet of wire are thus laid up in every cable; hence the risk of overheating is very great, and if overheated at many points there will be just so many 65 points of great lack of homogeneity in the cable liable to rupture if used; but a cable of solid strands of wire cannot be made even cold in the ordinary way. If the straight wires be wound or twisted when cold directly around 7c an interior flexible core, said core cannot resist the tendency of each wire not to accommodate itself to its new shape—in other words, to untwist.

In order to obviate all the above-named difficulties and disadvantages, my method of constructing wire cables is as follows: Each individual wire is first coiled around a mandrel of suitable form and diameter, or otherwise coiled or twisted by any suitable machinery to a 80 given pitch. This pitch should be slightly less than that which the wire will assume when laid up in the cable, and the internal diameter of such coil also should be smaller than that of the core to be used in the cable when a core 85 is used. These coiled or helical wires are then (each series where more than one series is used) laid up together or around or over the core of the cable under slight tension. By this special construction the wires are first coiled or twisted 90 separately instead of together, and then laid to each other when the cable is being made, and thus the cable is caused to maintain a certain force within itself, which tends to retain the various coils together, and thus 95 to resist any tendency in the strands to open or unwind when the cable is in use. This practice will by tension in laying up overcome any little irregularity in the helices and leave in the made-up cable the live force desired. 100

It is manifest, however, that, if desired, the helices can be made of exact diameter and

pitch to lay up properly without affecting the resulting cable disadvantageously. Such a cable is therefore not only elastic and compact, but can be constructed devoid of any core at 5 all, thus forming a hollow flexible tube composed of helices mutually coherent. Such construction may be used for many purposes where no core is necessary.

In the several figures of the drawings the 10 letter A, Figs. 1, 3, 4, and 6, indicates a flexible core of hemp or other flexible material; B, the external solid strands of wire; b, Fig. 2, one series of internal solid strands of wire; and c, Fig. 6, indicates a series of internal 15 laid-up strands of fine wires of ordinary construction.

The advantages of a cable made as herein 20 described can best be set forth by a short comparative description of the ordinary methods of making wire rope cables and of some of the 25 defects inherent in such cables, which it is the object of this invention to obviate.

The ordinary wire cable or rope for general 25 use is usually made in the following manner: A number of fine wires are first laid up or twisted together into a small rope or strand around a core. A number of these small strands, such as shown at c, Fig. 6, are then laid up or twisted together around a flexible hemp core 30 as a common center, and thus form a completed rope or cable. This construction has been found well adapted to the general uses to which wire cables have heretofore been put; but the increasing use of wire cables for traction 35 purposes has opened new fields of service of comparatively recent date, and it has been found that the ordinary construction above described is not well adapted for many purposes. The friction and abrasion to which the 40 fine wires of the ordinary cables are exposed

when such cables are used for traction purposes quickly destroy such wires with the consequent effect that the strands being thus injured the wires partially unwind and open out, causing the cable to "bunch" or become enlarged and out of truth wherever such injuries occur. The cable is thus soon rendered unfit for use.

To remedy the above-mentioned defect, the 45 solid strands of wire of comparatively large diameter above described are used in the cable herein described as the subject of this invention.

No claim is herein made for any core as an 50 article of manufacture, such a claim being now embodied in my pending application Serial No. 179,206, filed October 7, 1885.

Having thus fully described my said method 55 of making wire ropes or cables and the advantages of the cables so made as of my invention, I claim—

1. The method of making wire cables having 60 solid exterior strands hereinbefore described, consisting in first forming each individual solid strand into a helix when cold, and then winding or laying up said strands together into a cable, substantially as and for the purposes set forth.

2. The method of making wire cables having 65 solid exterior strands hereinbefore described, consisting in first forming each individual solid strand into a helix when cold, and then winding or laying up said strands together into a cable over an interior or core, substantially as and for the purposes set forth.

A. J. MOXHAM.

CHARLES P. LATTING,
GEO. C. AUSTIN.

It is hereby certified that in Letters Patent No. 337,513, granted March 9, 1886, upon the application of Arthur J. Moxham, of Johnstown, Penn., for an improvement in "The Method or Process of Making Wire Cables," an error appears in the printed specification requiring correction as follows: In line 54, page 2, the word "core" should read *cable*; and that the Letters Patent should be read with this correction therein that the same may conform to the record of the case in the Patent Office.

Signed, countersigned, and sealed this 30th day of March, A. D. 1886.
